UNITED STATES PATENT OFFICE.

SYLVENUS J. LACKEY, OF INDIANAPOLIS, INDIANA.

BOSOM-BOARD.

SPECIFICATION forming part of Letters Patent No. 325,346, dated September 1, 1885.

Application filed December 9, 1884. (No model.)

To all whom it may concern:

Be it known that I, SYLVENUS J. LACKEY, a resident of Indianapolis, Marion county, Indiana, have made certain new and useful Improvements in Bosom-Boards, a description of which is set forth in the following specification, reference being made to the accompanying drawings, in the several figures of which like letters indicate like parts.

10 My invention relates to the construction of boards for clamping shirts while ironing bosoms and neckbands, and will be readily understood from the following description.

15 In the drawings, Figure 1 is a front view of the board and its frame in place. Fig. 2 is a longitudinal section on line 2', Fig. 1; and Fig. 3 is a cross-section on 3, Fig. 1.

20 In detail, *b* is the bosom-board having a solid neck-piece, *n*, at its upper end, a slightly convex top, and a flat bottom having projections *p* on each side and on the lower end. If this board be made, as it may be, of two parts or layers, the lower half will thus be longer and wider than the upper half, for the purposes 25 hereinafter set forth.

25 *c* is a spring-catch fastened in the lower end of the board, connected by a stem passing through that end of the frame, with a push-knob, *k*, on the end for freeing the catch from its engagement with the frame. The upper end of the board is sloped or rounded, as shown in Fig. 1, and fastened to the under side of the board is a thin metal hook, *h*, which fits, hinge-like, over the central part, which is rounded, 35 of the upper end of the frame *f*. This frame is rabbeted out on both sides and the lower end to receive the projections on the lower part of the board *b*, and to such a depth that

the board *b* is allowed to rise some distance above the plane of the top of the frame *f*, as shown in Fig. 3.

This construction is peculiar, and the shirt being placed over the board, the neck-yoke surrounding the neck-piece *n*, the bosom over the bosom-board, the shirt is drawn evenly and stretched over the board, the end of the frame *f*, hinged in the hook *h*, the frame pushed down over the board, and by means of the projections *p* on sides and end and rabbet *r* a firm grip is taken on the goods, and the catch *c*, engaging with the board, the shirt is securely held in place, and may thus be ironed easily and smoothly. The edges or shoulders of the board projecting above the sides of the frame assist materially in holding the shirt down even, and the peculiar clamp formed by the arrangement of the parts is strong, easily worked, and serviceable.

I am aware that bosom-boards having neck-pieces and boards provided with frames are not new, and do not broadly claim the same as my invention; but

What I claim, and desire to secure by Letters Patent, is the following:

The bosom-board *b*, having projections *p* on its sides and lower end and solid neck-piece *n*, hook *h*, frame *f*, with rabbets *r* on its sides and lower end, arranged so that board *b* projects above the plane of the sides of frame *f*, and spring-catch *c*, all combined substantially as described.

Witness my hand, November 3, 1884.

SYLVENUS J. LACKEY.

Witnesses:

C. P. JACOBS,
H. B. MAKEPEACE.
